UNITED STATES PATENT OFFICE.

ROBERT R. BLAIR, OF ALAMOGORDO, NEW MEXICO.

CONCRETE RAILROAD CROSS-TIE.

1,192,739.

Specification of Letters Patent. Patented July 25, 1916.

Application filed May 28, 1915. Serial No. 30,981.

To all whom it may concern:

Be it known that I, ROBERT R. BLAIR, a citizen of the United States, residing at Alamogordo, in the county of Otero and State of New Mexico, have invented certain new and useful Improvements in Concrete Railroad Cross-Ties; and I do hereby declare the following to be a full, clear, and exact description of the invention, such as will enable others skilled in the art to which it appertains to make and use the same.

This invention relates to improvements in railway ties and rail fasteners and especially with reference to a reinforced concrete railway tie and improved means for fastening the rails on the tie, to keep the rails from spreading, one object of the invention being to effect improvements in the construction of the tie, another object being to effect improvements in the construction 20 of the rail fastening devices.

The invention consists in the construction, combination and arrangement of devices hereinafter described and claimed.

In the accompanying drawings:—Figure 1 is a plan of a railway tie constructed in accordance with my invention, and also showing the rails and rail fastening devices. Fig. 2 is a side elevation of the same with the rails in cross section. Fig. 3 is a transverse sectional view of the same on the plane indicated by the line 3—3 of Fig. 2. Fig. 4 is a similar view of the same on the plane indicated by the line 4—4 of Fig. 3. Fig. 5 is a vertical longitudinal sectional view of the same on the plane indicated by the line 5—5 of Fig. 1. Fig. 6 is a similar view on the plane indicated by the line 6—6 of Fig. 1. Fig. 7 is an end elevation of the same. Fig. 8 is a detail perspective view of one of the cushioning blocks. Fig. 9 is a detail inverted plan of the tie and its connections.

The tie 1 is of oblong rectangular form with vertical sides 2 vertical ends 3 a flat horizontal top 4 and with the bottom or lower side 5 provided with transverse corrugations 6 which engage in the road bed and prevent the tie from slipping. The tie 50 is made of concrete and is molded in a suitably constructed mold.

In the center of the tie and extending from end to end thereof is a reinforcing rod 7 made of iron or other suitable material and the ends of which are turned down at right angles as at 8 and, being em-

bedded in the concrete material of the tie, is by reason of the provision of its downturned ends effectually locked and materially increases the strength of the tie. Above 60 and below the central longitudinal rod 7 and in vertical alinement therewith are shorter reinforcing rods 9 which are also embedded in the material of the tie while the latter is being molded and have downturned keying or locking ends 10. By the provision of these centrally arranged shorter reinforcing rods the central portion of the tie is strengthened and the same is prevented from breaking.

At a suitable distance from the sides and top and bottom of the tie are outer longitudinally arranged reinforcing rods 11 which extend from end to end of the tie and have downturned keying or locking 75 ends 12. Shorter reinforcing rods 13 are also provided which are arranged in the central portion of the tie, in vertical alinement with the rods 11 and have downturned keying or locking ends 14.

In the upper side of the tie at a suitable distance from its ends are recesses 15 which extend across the tie and form seats for the reception of cushioning blocks 16 which may be made of wood, preferably oak, or of any 85 other suitable material and the width of which exceeds that of the bases of the rails 17. The rails bear on the said cushioning blocks.

The tie is provided with bolt holes for 90 the reception of bolts 18, the heads 19 of the bolts being square or non-circular and fitted in recesses in the lower side of the tie and hence the bolts are prevented from turning. The bolts extend up above the tie at 95 points immediately on opposite sides of the rail bases, and through notches 20 in the sides of the cushioning blocks 16. Rail fastening blocks 21, of iron or steel are provided with openings through which the 100 bolts extend and also with arms 22 which extend over and engage the bases of the rails, said securing blocks bearing directly on the tie and being secured in place by means of nuts 23 which are screwed on the 105 bolts.

The transverse corrugations in the bottom of the tie prevent the same from slipping. The reinforcing rods, with their angularly bent keying ends, greatly strengthen the 110 construction of the tie and the cushioning blocks absorb the shocks from the rails and

afford the necessary resilience. The bolts, with their locking blocks and nuts, and by reason of the attachment of the bolts to the tie, securely fasten the rails on the tie and 5 effectually prevent the rails from spreading.

Having thus described my invention I claim:—

A concrete tie rectangular in cross section having a series of longitudinally extending reinforcing bars embedded centrally therein and spaced apart, a second series of longitudinally extending reinforcing rods arranged in spaced relation to the top and bottom of the tie, and located between the 10 first named bars, said rods extending from end to end of said tie, each of said rods and bars provided with downturned ends for

anchoring said rods and bars within the body of the tie, and vertical bolts inserted up through said tie, one end projecting beyond one face thereof, their opposite ends embedded in the under surface of said tie preventing rotation of the same, and the bottom of said tie having transverse corrugations thereon, the convolutions of which 20 are arranged in the horizontal plane preventing movement of the said tie upon a road bed. 25

In testimony whereof I affix my signature in presence of two witnesses.

ROBERT R. BLAIR.
